H. MOORE.
PAPER CUP HOLDER.
APPLICATION FILED SEPT. 15, 1917.

1,389,594.

Patented Sept. 6, 1921.

FIG. 3

FIG. 4

FIG. 1

FIG. 2

Inventor
Hugh Moore,
By his Attorney
Clifford E. Steiner

UNITED STATES PATENT OFFICE.

HUGH MOORE, OF LEONIA, NEW JERSEY, ASSIGNOR TO INDIVIDUAL DRINKING CUP COMPANY, INC., A CORPORATION OF NEW YORK.

PAPER-CUP HOLDER.

1,389,594.

Specification of Letters Patent. Patented Sept. 6, 1921.

Application filed September 15, 1917. Serial No. 191,572.

To all whom it may concern:

Be it known that I, HUGH MOORE, a citizen of the United States, residing at Leonia, county of Bergen, State of New Jersey, have invented new and useful Improvements in Paper-Cup Holders, of which the following, taken in connection with the accompanying sheet of drawings, is a full, clear, and concise description thereof.

10 The use of paper drinking cups or receptacles has extended in recent years to the soda fountain, where ice cream sodas, mixed drinks, etc., are served, the character of which generally requires the use of spoons 15 in their consumption.

Various forms of paper drinking cups have been manufactured. A convenient form is one in which the bottom of the cup is a separate piece from the side wall and 20 is raised a short distance above the lower edge of the side wall thereof. In other words, the lower edge of the side wall of the cup extends somewhat below the bottom of the cup which is made of a separate circular disk of paper.

25 My present invention relates to certain improvements in cup holders for paper cups and the combination of cup and holders, particularly adapted for use with paper drinking cups, made of light, fragile material which may be ruptured by use of a spoon or other utensil against the sides or bottom of the paper cup, when filled with liquid.

30 One of the objects of this invention is to provide an immediate or direct support for the bottom and lower side walls of the paper cup to prevent the cup from being ruptured when a spoon or other utensil is jammed against it with sufficient force to rupture 35 or displace the fragile side wall or bottom, were it unsupported.

Another object of this invention is to provide a holder in such form that it will catch and retain any small amount of liquid that 40 might drip or flow over the outside of the cup.

45 Another object of this invention is to provide a sufficiently extended base for the holder so that the holder and the light, 50 fragile paper cup, filled with liquid, will not be easily upset when placed upon the counter or table.

In referring to the accompanying drawings, I have illustrated a preferred embodiment of my invention, and will proceed to

describe the same, having it understood that the form is merely illustrative and structural changes may be resorted to without departing from the spirit and scope of the invention as defined by the appended claims. 60

Figure 1 is a view in elevation of one embodiment of my invention.

Fig. 2 is a sectional view on the line *a a* of Fig. 1.

Fig. 3 is a top plan view of a cup holder 65 and cup with a part of the cup broken away to show the interior of the cup holder.

Fig. 4 is a sectional view of a paper cup, being used without the holder showing the position of a spoon therein in dotted line, 70 at the instant of rupture.

The cup as shown is preferably frusto-conical in form, having a bottom raised above the lower edge of the side wall, upon 75 which the cup rests.

Referring to the accompanying drawings in detail, 1 represents one form of cup holder made according to my invention and 2 a paper cup contained within the holder, 3 the support for the bottom of the paper 80 cup, 4 an annular depression or recess adapted to receive the lower extended portion of the side walls of the cup and any small amount of drippings which may trickle over the outside of the cup. 5 represents the extended base of the holder and 6 the upper out-turned lip of the holder which will catch the small drippings and direct them downwardly through grooves 7 between the outside of the cup and the inside of the holder. 85 I prefer to employ a cup of such size as will just fit within the holder.

In Fig. 4 wherein a cup is shown in use without a holder, 9 represents a spoon (in dotted lines) pressed downwardly against 90 the paper bottom 8 with sufficient force to distort it as shown at 8^a unless it is supported in some way other than by its own strength. 10 represents the base of the paper cup formed by the lower edge of the 100 rim thereof.

When the cup 2 of the proper size—that is to say, of a slightly lesser diameter than that of the interior of the holder, is inserted into the holder as shown in Fig. 2, its bottom 105 8 will rest upon the raised portion 3 of the base of the holder 1, the lower edge of the supporting rim 10 of the cup extending into the annular depression or recess 4. The fragile bottom of the cup, it will be seen, is 110

thus positively and directly supported by the raised portion 3 of the base of the holder 1, so that it will be impossible to distort or rupture the bottom 8 of the cup by the spoon 9, or other utensil used in dispensing the beverage contained in the cup being brought into ordinary contact with said bottom. Furthermore, the wall of the cup is supported by the wall of the holder and by forming my holder in the manner illustrated and described, it will be obvious that the paper cup is not only protected against rupture and consequent spilling of its contents, but it is possible to fill the cup with beverages of liquids, or combinations of liquids and solids of a greater weight than the unsupported cup could hold.

The out-turned lip 6 of the holder 1 or the wall of the holder adjacent to the lip is formed with grooves or depressions 7 to provide for the retention of the drippings or the overflow from the cup within the holder, the drippings passing through the grooves or depressions 7 down the interior of the wall 25 of the holder into the depression or recess 4 formed in the base thereof.

When a cup holder with the raised bottom is used, it supports the bottom of the paper cup and in ordinary use is less likely to rupture the bottom and almost impossible to cut a hole through the paper bottom with the ordinary spoon, thus permitting the use of individual paper drinking cups at soda fountains where spoons and other utensils are used in the paper cup and proves a very important adjunct in the sanitation and cleanliness of such places.

Having thus described one embodiment of my invention what I claim as new herein and 40 desire to secure by Letters Patent is—

1. A holder for paper cups having a base and side walls, said base having an interiorly formed annular depression providing a raised support for the bottom of a paper cup, whereby the bottom of the cup will not be subject to distortion by the contact of a spoon or a like utensil therewith.

2. A holder for paper cups formed with an outwardly extending lip at the top thereon and a supporting base, said supporting base having an interiorly formed annular depression to provide a raised annular support, the periphery thereof being spaced inwardly from the wall of the base of the holder.

3. A holder for a paper drinking cup having a lower rim and a bottom spaced upwardly therefrom, said holder having a wall for supporting the wall of the cup, a base 60 and an interiorly formed annular depression in said base providing a raised support for the bottom of the paper cup, the lower rim of the cup extending into the said depression.

65 4. A holder for a paper drinking cup

having a lower supporting rim and a bottom spaced upwardly therefrom, said holder being formed to support the side wall of said cup and including a base having an interiorly formed annular depression providing a centrally located raised portion to directly support the bottom of the cup when placed in the holder, whereby the supporting rim of the cup will extend into the base of said holder, and rupture or distortion of the bottom of the cup by a spoon, or like utensil coming in contact therewith will be prevented.

5. A holder for paper cups having a side wall formed with an out-turned lip surrounding its upper edge, a supporting base having a portion to reinforce the wall of the cup, and a depression formed therein providing a raised support adapted to underlie the bottom of the paper cup to constitute a rest for the latter and means of communication between the lip of the holder and the depression in the base thereof, whereby the overflow of the contents of the cup contained in said holder will be retained in the depression in the base thereof until the cup is removed from the holder.

6. A holder for a paper cup formed with a supporting rim and a bottom spaced upwardly therefrom, said holder having a wall to support the wall of the cup, a base, and a bottom spaced upwardly from said base and having a portion formed to provide a direct support for the bottom of the paper cup.

7. A holder for a paper cup having a supporting rim extending below the horizontal plane of the bottom of the cup, said holder having a wall to support the wall of the cup, an outwardly extending base and a bottom spaced upwardly from the lower supporting surface of the base, and having a portion formed to project within the supporting rim of the paper cup and providing a direct support for the bottom of the paper cup, the area of said support being substantially co-extensive with that of the paper bottom of the cup.

8. A holder for paper cups of a frustoconical configuration having a lower supporting rim and a bottom spaced inwardly therefrom, said holder having a side wall tapering downwardly from the upper edge thereof to support the wall of the cup, an annular base of a greater diameter than the diameter of the mouth of the holder and a bottom spaced upwardly from the supporting surface of the base, and having a raised portion adapted to lie within the supporting rim of the cup when placed in the holder and directly supporting the bottom of the cup for the purposes described.

9. Means for supporting and rendering thin paper cups, designed for a single service and immediate destruction, capable of use in a manner for which they are alone inca-

- pable comprising means for engaging and bracing the surrounding paper wall of the cup, said means being formed to snugly receive said wall to prevent bulging of the latter under interior weight or manipulation of the cup contents, and means including a surface on which the bottom of the cup may bear over substantially its entire area to resist displacement or puncture of said bottom under manipulation of the cup contents by a spoon or the like.
10. Means for supporting and rendering thin paper cups, designed for a single service and immediate destruction, capable for use in a manner for which they are alone incapable, comprising means for engaging and bracing the surrounding paper wall of the

cup, said means being formed to snugly receive said wall to prevent bulging of the latter under interior weight or manipulation of the cup contents, and means including a surface on which the bottom of the cup may bear to resist displacement or puncture of said bottom under manipulation of the cup contents by a spoon or the like, said bottom supporting means occupying an elevated position with its marginal edge approximately in line with the cup wall bracing means but offset slightly inwardly therefrom to accommodate any depending flange portion on the cup.

In witness whereof I have hereunto set my hand.

HUGH MOORE.
